UNITED STATES PATENT OFFICE.

REMY FREDERICKS, OF SAN FRANCISCO, CALIFORNIA.

DESIGN FOR A SPOOL-HOLDER OR TOY.

52,819.

Specification for Design.

Patented Dec. 31, 1918.

Application filed January 31, 1918. Serial No. 214,784. Term of patent 3½ years.

To all whom it may concern:

Be it known that I, REMY FREDERICKS, a citizen of the United States, residing in the city and county of San Francisco and State of California, have invented a new, original, and ornamental Design for a Spool-Holder or Toy, of which the following is a specification, reference being had to the accompanying drawings, forming part thereof.

Figure 1 is a view in front elevation of the spool holder or toy showing my new design.

Fig. 2 is a view in side elevation of the same.

I claim:

The ornamental design for a spool holder or toy, as shown.

REMY FREDERICKS.

Witnesses:

F. P. PLAYEMANN,
E. I. JENSEN.
